UNITED STATES PATENT OFFICE.

GEORGE EVANS WEBB, OF MILWAUKEE, WISCONSIN, ASSIGNOR TO KOEHRING COMPANY, OF MILWAUKEE, WISCONSIN, A CORPORATION.

THREE-WAY SWINGING VALVE FOR CONCRETE MIXERS.

Application filed June 5, 1925. Serial No. 35,176.

In the construction of concrete mixing machines, it has heretofore been proposed to employ certain three-way valve means for governing the passage of water from a supply line to the measuring tank that controls the quantity of water to be fed to the mixing drum. This three-way valve mechanism also controls the passing of the water from the measuring tank to the mixing drum. Letters Patent of Lichtenberg, 1,525,100, issued February 3, 1925, illustrates a type of such three-way valve mechanism upon which the present invention is an improvement.

The primary object in designing the present improvement has been to produce valve means which is constructed and operates in such a way as to provide a virtually unobstructed passage through which the water may move from the measuring tank into the mixing drum. That such a free or unobstructed passage is highly desirable for the practical operation of concrete mixers of the paver type is understood. Requirements governing the operation of such mixers are beginning to specify that the water must be introduced into the mixing drum before the user of the machine starts to measure the time of the mixing period. Usually, a minimum mixing period of a minute or a minute and a half is specified for each batch of aggregates handled in the drum.

It has heretofore required a longer time to introduce the water into the drum than to introduce the solid aggregates, and the present invention provides the means for cutting down materially the time factor consumed in the water introducing operation, the aim being to get the water into the mixing drum about as quickly as it is possible to introduce the solid aggregates; therefore, there will be no loss of time in measuring the mixing period after the solid aggregates have been charged into the mixer. This loss of time heretofore has been represented by the necessity of waiting for the water to get into the drum in states where it is required that the water and solid aggregates be in the drum at the "zero hour" of the mixing period, which in other words is the commencement time of said period.

In the carrying out of the present invention, the piping system running from the measuring tank to the mixing drum is so

made that no sharp turns, obstructing partitions, valves, pistons or the like are interposed in the path of the water as it passes from the measuring tank to the said drum. A novel type of pivoted valve is utilized in conjunction with a piston involving certain of the principles of the Lichtenberg patent previously referred to, but is arranged and operates in an essentially different manner.

Among other objects of the invention are the provision of a special casing construction, pivoted valve, and a counterbalancing piston device, means facilitating free removal and replacement of the parts, also means for producing a quick opening and closing movement of the valve as a supplement to the action of the main operating means by which such action is initiated.

In the accompanying drawings:

Figure 1 is a side view of the frame work of the concrete paving machine showing the preferred embodiment of the invention applied thereto;

Fig. 2 is an enlarged side view of the valve mechanism;

Fig. 3 is a view similar to Fig. 2, but taken from the point at right angles thereto;

Fig. 4 is a vertical sectional view through the valve casing, illustrating clearly the valve and piston members and connections;

Fig. 5 is a top plan view of the valve casing;

Fig. 6 is a side view of the measuring tank valve mechanism ordinarily known as the measuring valve; and

Fig. 7 is a detail view of the guide means for the skip actuated rod.

Referring to the drawings, and primarily to Figure 1, the frame work of the machine which is usually mounted upon a portable base, not illustrated, is designated as A. Suitably supported in the frame work is the mixing drum 1, having the feeding chute 2 adapted to be used when supplying the drum 1 with a charge of solid aggregates by means of the skip 3. The skip 3 is raised and lowered in the well known manner by means not shown. Above the mixing drum 1 is disposed the measuring tank 4 from which leads an outflow passage provided by a pipe 6 suitably connected with the casing 7 of the three-way valve mechanism which, in turn, is connected with the mixer supply

pipe 8. The three-way valve mechanism comprises the main casing 7 for the three-way valve, and a piston casing or chamber 9 suitably connected with a water supply line pipe 10. This pipe 10 leads from a suitable source of water supply, and the water enters the valve casing parts 7-9 at a pressure which ranges usually from thirty pounds to one hundred and fifty pounds depending upon the source of supply. It is notable that the pipes 6 and 8 are of relatively large diameter for facilitating the flow of water from the tank 4 into the mixing drum 1, and that the arrangement of the said pipes, when connected by the casing 7, is such that the water flows through the passage formed by these parts, with only a slight curve in the passage, as said water passes from the tank 4 to the drum 1.

20 The manner in which the three-way valve is mounted so as not to obstruct the passage of water from the casing 7 will now be set forth by particular reference to Fig. 4.

25 Referring to Fig. 4, the valve casing 7 will be seen as having a port 7^a with which the pipe 6 is connected, also this casing 7 has the outflow port 7^b with which the pipe 8 communicates. At the outflow port 7^b, the casing 7 is equipped with a valve seat 11, against which the valve 12 is adapted to cooperate. The valve 12 is provided with a member 13 connected by the link 14 with a similar member 15 of the counter-balancing piston 16 which operates in the piston chamber 17 of the water inlet casing or chamber 9 of the valve mechanism. The piston chamber 17 is located in the casing or chamber 9, there being a cored space between the two which constitutes a water inlet space into which directly leads the water supply main line pipe 10.

30 The valve 12 is pivoted by means of the provision of a pivot shaft 18 near the uppermost outer portion of the casing 7. The casing part 9 is detachably connected as by fastenings 19 to the casing 7. An opening is provided at the top of the casing 7 communicating with a corresponding opening in the bottom of the casing part 9, said bottom opening being equipped with a detachable valve seat 20. This construction is such that the water entering the casing part 9 is adapted to flow freely and downwardly through the opening in the bottom of the said part 9 and the opening in the top of the casing 7 into the latter casing, whereupon, if the valve 12 is in the position of Fig. 4, the water will flow to the measuring tank 4 through the port 7^a. If the valve 12 is raised, and is in an open position, the water will flow through the port 7^b and pipe 8 into the mixing drum 1.

35 The valve 12 is a disc type valve, such construction being preferable because it may be provided with soft or semi-soft discs on its

opposite faces for cooperation with the valve seats 11 and 20. The piston chamber 17 may be provided with a brass lining (not shown), rolled into the bore, and flared at its upper end to avoid displacement. The valve seat 20 is preferably of brass, screwed into the bottom of the casing part 9. A non-ferrous valve seat may thus be used and corrosion of seat and rapid deterioration of valve avoided. The piston 16 is preferably made 75 of two brass discs, between which is mounted the usual leather cup washer. The valve 12 preferably comprises a body having opposite recesses in which are mounted the soft or semi-soft valve discs 12' and 12'', the disc 80 12'' co-acting with the seat 20 and the disc 12' with the seat 11. The axis of the shaft 18 is provided by boring through the extension 7^c of the casing 7. The bored hole for the shaft 18 provides an axis for the 85 pivotal or swinging movement of the valve 12 and said valve has a pivoted extension 12^a provided with a square hole in which fits loosely a squared portion of the shaft 18. The loose fit of the shaft 18 in the extension 90 12^a of the valve 12 is designed to provide for some flexibility or looseness in the mounting of the valve which will permit it to adjust itself freely for proper and accurate seating against either of the cooperating valve seats. One end of the shaft 18 is adapted to project from the casing 7 from either side of the casing, the shaft being interchangeable in its mounting for such purpose. A screw plug 22 is used to close the 100 end of the opening in the casing 7, receiving said shaft 18, and opposite the end from which the shaft projects, as seen best in Fig. 3. The projected end of the shaft 18 carries an operating lever 23, and preferably passes through a stuffing box 24 of any ordinary type. The lever 23 is keyed to the shaft 18 and adjacent to said lever 23 is a trip lever 25, loose upon the shaft 18 to the extent that it may be rotated. The lever 25, however, is prevented from displacement from the shaft 18 by a pin 26 engaging with an annular groove 27 in the outer end of said shaft. As seen best in Fig. 2, there is connected with the lower free end of the 110 lever 25, a push rod 28 having a slot 29 through which a pin 30 of the lever 25 passes. The push rod 28 is connected with a link rod 31, with which is connected a hand lever 32 pivoted on the frame work 115 A of the machine. The lever 25 is equipped with oppositely extending curved arms 25' having lateral lugs 25'' engageable with the lever 23. Said lever 25 is also provided with an outwardly projecting pin or stud 33 having connected therewith a coil spring 34 attached to it at one end, the opposite end of said spring being secured to a projecting arm 35 extending from the top plate 36 120 of the casing part 9.

130

With the parts constructed according to the foregoing explanation, the general operation of the device is as follows:

It will be assumed that the parts are in the positions of Figures 1 and 2. The skip 3 is raised to charge the drum 1 with heavy or solid aggregates. As the skip 3 reaches an angle of approximately 20° above the grade, a roller member 3^a strikes a bend 28^a of the rod 28. The rod 28 is forced to the left to correspondingly actuate the lever 25, having increased the tension of the spring 24 to the maximum degree used. At a predetermined point in the movement of the rod 28 to the left, the outermost inclined end 28^a of the rod 28 by cam action or a roller 36 is raised so that the roller 3^a of the skip 3 is disengaged from the bend 28^a of the rod 28 permitting the skip to continue its movement upwards without forcing said rod 28 farther. The movement of the rod 28 was sufficient, however, under actuation of the skip 3 to shift the lever 25 over the dead center of its movement in cooperation with the spring 34 so that said spring 34, after the valve 12 is raised from its seat 11 by said actuation of the rod 28, will quickly impart a final rising movement to the valve 12 to cause it to assume its uppermost position in the casing 7, substantially in a plane above the port 7^a, communicating with the tank. When in this position, the valve 12, which has previously cut off communication from the tank 4 and the mixing drum 1, permits a free flowing of the measured quantity of water from the tank 4 into the drum 1 through the pipes 6, casing 7, and pipe 8. The flow of the water is wholly unobstructed by the valve in such operation. After the measured quantity of water has passed through the drum 1, the operator by moving the hand lever 32, may return the valve 12 to its position against the seat 11, and cut off communication from the tank 4 to the drum 1, at the same time reestablishing communication between the supply line pipe 10 and said tank 4; so that the tank may be refilled.

It is notable that when the valve 12' is raised to the position just above described for admitting water to the drum 1, said valve becomes seated against the seat 20 and cuts off communication from the casing part or chamber 9, through which the water enters from the main line pipe 10, and said port 7^a, thus discontinuing the supply water to the tank. In returning the valve 12' by the hand lever 32, the spring 34 acts to cause a final quick movement of the valve in exactly the same way as the spring acted previously to cause the final accelerated movement of the valve against its position on the seat 20. Necessarily, the action of the hand lever 32 will restore the rod 28 to its normal position, first referred to.

It is not necessary for the purpose of this invention to operate the rod 28 from the skip 3 to open communication from the tank 4 to the drum 1. This may be done manually, if desired. It is noticeable, furthermore, with reference to Fig. 6, that the measuring tank involves the measuring means comprising the measuring pipe 37 in the tank 4 adapted to be raised and lowered by turning the handle 38 which operates the worm 39 co-acting with a worm gear secured on the pipe 27. As this mechanism forms a separate invention from that described in detail herein, further description thereof is believed not warranted. Any suitable type of measuring valve mechanism may be provided in the tank 4.

Referring to Fig. 4, it is noticeable that the area of the valve seat 11 is larger than that of the balancing piston 16, and the area of the valve seat 20 is less than that of the piston 16. The water pressure from the main line, therefore, acts upon the piston 16 to substantially balance the pressure on the valve 12. The pressure is not completely balanced because it is desirable that when the valve is in the lower position of Fig. 4, pressure of the water from the main line will assist or tend to hold the valve 12 closed. Furthermore, when the valve 12 is seated against the seat 20, since the area of the piston 16 is greater than that of the seat 20, the pressure of the water against the piston 16 tends to hold the valve 12 against the said seat 20. In effect, therefore, the water pressure cooperates to maintain the valve 12 in either one of its two positions, co-acting with the two seats 11 and 20. It is possible with in the purview of the invention to dispense with the spring 34, but said spring is desirably used to maintain as closely as possible a timing of the opposite movement of the valve 12 which is substantially constant, rendered so by the mechanical action of the spring on the valve.

Having thus described my invention, what I desire to secure by Letters Patent is:

1. In combination, a valve casing having a water inflow port, a tank port and a mixer outflow port, means to swingingly mount the valve in the casing so that when it is moved from a position closing the mixer outflow port to a position closing the water inflow port, it will not obstruct the passage of the water through the tank port and casing out of the outflow port, a piston chamber in communication with the water inflow port, a piston mounted in said chamber, and connecting means between said piston and the valve.

2. In combination, a valve casing having a water inflow port, a tank port and a mixer outflow port, means to swingingly mount the valve in the casing so that when it is moved from a position closing the mixer outflow

port to a position closing the water inflow port, it will not obstruct the passage of the water through the tank port and casing out of the outflow port, a piston chamber in communication with the water inflow port, a piston mounted in said chamber, and connecting means between said piston and the valve, the water inflow port being of a smaller area than said piston and the valve being of a greater area than said water inflow port for the purpose set forth.

3. In a valve mechanism of the class described, in combination, a valve casing having an upper water inflow port, a tank supply port, and a water mixer outflow port, a valve adapted to swing from a position closing the outflow port to a position closing said water inflow port, in which position said valve moves past the tank supply port so as not to obstruct the passage of water through said tank supply port to the mixer outflow port, a counterbalancing piston associated with the valve and arranged so that water entering said inflow port under pressure will act upon said piston at the same time that it acts upon said valve, and a connection between the piston and the valve.

4. In a valve mechanism of the class described, in combination, a valve casing having an upper water inflow port, a tank supply port, and a water mixer outflow port, a valve adapted to swing from a position closing the outflow port to a position closing said water inflow port, in which position said valve moves past the tank supply port so as not to obstruct the passage of water through said tank supply port to the mixer outflow port, a counterbalancing piston associated with the valve and arranged so that water entering said inflow port under pressure will act upon said piston at the same time that it acts upon said valve, a connection between the piston and the valve, the water inflow port being of smaller area than the piston, and the valve area being greater than that of said inflow port.

5. In a valve mechanism of the class described, in combination, a valve casing having an upper water inflow port, a tank supply port, and a water mixer outflow port, a valve adapted to swing from a position closing the outflow port to a position closing said water inflow port, in which position said valve moves past the tank supply port so as not to obstruct the passage of water through said tank supply port to the mixer outflow port, a counterbalancing piston as-

sociated with the valve and arranged so that water entering said inflow port under pressure will act upon said piston at the same time that it acts upon said valve, a connection between the piston and the valve, said connection being a link, and means for operating the valve including a device for automatically accelerating the movement of the valve after preliminary mechanical shifting of the same.

6. In a valve mechanism of the class described, in combination, a valve casing having an upper water inflow port, a tank supply port, and a water mixer outflow port, a valve adapted to swing from a position closing the outflow port to a position closing said water inflow port, in which position said valve moves past the tank supply port so as not to obstruct the passage of water through said tank supply port to the mixer outflow port, a counterbalancing piston associated with the valve and arranged so that water entering said inflow port under pressure will act upon said piston at the same time that it acts upon said valve, a connection between the piston and the valve, said connection being a link, means for operating the valve including a device for automatically accelerating the movement of the valve after preliminary mechanical shifting of the same from either of its positions co-acting to close the mixer outflow port or the water supply port, and means supporting the valve in a slightly loose manner so that it may adjust itself for accurate seating against seats provided at said water inflow port and said mixer outflow port, said seats located at the ports above last mentioned.

7. In combination, a water tank, an unobstructed passage leading from the water tank adapted to lead to a mixer, together with a valve located in said passage and movable from a position cutting off communication between the water tank and the mixer to a position establishing such communication, a mounting for the valve permitting it to move into the last mentioned position so that it is out of the way of water passing from the tank to the valve through the passage, means associated with the valve for substantially counterbalancing the inflow pressure thereon, and a water supply line pipe connected with said passage to supply water to the tank and adapted to be cut off from communication with the tank by said valve.

In testimony whereof I affix my signature.

GEORGE EVANS WEBB.
